CLAIM

The ornamental design for a optical active connector, as shown and described.

DESCRIPTION

FIG. 1 is a perspective view of the top, front and left side of an optical active connector showing our new design;

FIG. 2 is a perspective view of the bottom, front and right side thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines shown in the drawing are for illustrative purposes only and form no part of the claimed design.
